UNITED STATES PATENT OFFICE.

TREMONT W. RICKEL, OF McALLEN, TEXAS.

WINDOW-SASH LOCK.

Application filed August 6, 1925. Serial No. 48,676.

To all whom it may concern:

Be it known that I, TREMONT W. RICKEL, a citizen of the United States, residing at McAllen, in the county of Hidalgo and State of Texas, have invented certain new and useful Improvements in Window-Sash Locks, of which the following is a specification.

This invention relates to improvements in locking devices and has particular reference 10 to locks for window sashes and the like.

An important object of the invention is to provide a locking device which will automatically lock a window sash when in the closed position.

15 A further object of the invention is to provide a locking device of the above character whereby a window sash may be opened to a predetermined restricted position.

Another object of the invention is to provide means in window sash locking mechanism for entirely opening a window sash 20 when desirable.

Another object of the invention is the provision of sash locking mechanism of this 25 character which is comparatively simple yet durable in construction, and which can be placed upon the market at a relatively low cost.

Other objects and advantages of this invention will become apparent as the description progresses.

In the accompanying drawings forming a part of this specification and in which like numerals are employed to designate corresponding parts throughout the same:

Figure 1 is a fragmentary side elevational view of a window frame and sashes showing my improved apparatus mounted in association therewith,

40 Figure 2 is a horizontal sectional view of the same,

Figure 3 is a vertical sectional view through the window frame and locking apparatus, with the window sashes in closed 45 position,

Figure 4 is a similar view showing the bottom sash in a partially elevated position,

Figure 5 is a central vertical sectional view through my improved locking apparatus, and

Figure 6 is a central horizontal sectional view through the same.

In the drawings, wherein for the purpose of illustration is shown the preferred embodiment of my invention, the numeral 10 generally designates a conventional form of

window frame having slidably mounted therein an upper sash 11 comprising a sash frame 12, and a window pane 13, and a lower sash of similar construction 14. This 60 construction is conventional and forms no part of my invention, being merely shown to illustrate the application of my improved mechanism.

Referring now more particularly to the 65 structure embodying my invention, my improved device contemplates the provision of locking mechanism 15 adapted to be secured on the top rail of the lower window sash 14 co-operating with a guide frame 70

generally designated by the numeral 16 mounted on the side rail of the upper window sash for automatically locking the lower sash when it is forced downwardly to a closed position. The guide frame 16 is pref- 75

erably of integral construction embodying a central partition strip 17 reinforced along its outer longitudinal edge by the provision of a metallic rod and having its inner edge secured over the greater portion of its length 80 to a base plate 18. This base plate embodies a longitudinal base strip 19 extending substantially the entire length of the center strip 17 and a comparatively short base strip 20 disposed on the opposite side of the center 85

strip extending approximately one half the length of this strip. The outer longitudinal edges of the base plate 18 are provided with side strips 21 forming a comparatively long and a comparatively short guide way dis- 90

posed at each side of the partition strip 17. The lower ends of the parallel guide ways are open and likewise the upper end of the shorter guide way. The longer guide way on the other hand, is provided with an end 95

plate 22 forming a stop member so as to permit limited elevation of the lower window sash, as will be more completely described as the description progresses. This 100

guide frame structure 16 is securely fastened 105 against the inner side of the upper sash side rail by means of wood screws 23 inserted through suitable openings in the base plate 18 and threadedly engageable with the sash rail, the heads of these screws being prefer- ably countersunk to facilitate the operation of the locking mechanism.

The lower portion of the center partition strip 17 is recessed adjacent its connecting edge so as to provide an angular slot be- 110

tween this portion of the partition strip and the base plate. This construction is neces-

sary to permit the provision of a resilient bar member 24 preferably constructed of spring steel. This member is secured adjacent its upper end to the base plate 18 through the medium of suitable screws while its lower extremity normally extends in an outwardly directed position against the under side of the partition strip. This spring member 24 extends across the entire width of the base plate so as to engage the locking mechanism at either position in the guide frame.

Operatively associated with the guide frame and spring member mounted therein is a locking mechanism embodying a substantially rectangular casing 25, the forward end of the casing being provided with elevated side walls as at 26 and enclosed by the top plate 27. An angular cover plate 28 is hingedly connected with the cover plate 27 so as to enclose the remainder of the casing, the bottom of the casing being provided with a plurality of openings to receive wood screws 29 by means of which the casing is secured upon the head rail of the sash frame. Mounted in the central portion of the casing and secured to the bottom thereof is a longitudinally extending lever sleeve 30. This sleeve is secured to the bottom of the casing by extension plates 31 formed on the lower portion thereof, welded or otherwise secured in position. Longitudinally movable in the sleeve 30 is an angular locking lever 32 of metallic construction preferably circular in cross section embodying a longitudinal body portion 33 provided with right angular horizontally extending arm 34 at its forward end and a comparatively short vertical extension 35 at its rear end. The forward extension 34 is directed toward the upper companion sash 11 and projects substantially through a longitudinal slot 36 formed in the inner side wall of the casing 25. The rear extension 35 is directed upwardly and projects through a similar slot 37 formed in the angular cover 28; the slots 36 and 37 being similar in construction to permit predetermined movement of the locking lever 32. In order that the slot 37 formed in the angular cover plate 28 may be closed at all times, a substantially U-shaped plate 38 is slidably mounted on the casing, this plate being apertured to receive the upwardly directed extension 35 so as to cause the plate to reciprocate with the locking lever. The lever is actuated through the medium of a knob 39 threadedly or otherwise secured upon the upper projecting extremity of the extension 35. From the foregoing construction, it can be readily seen that the lever 32 may be reciprocated laterally in the casing 25, being limited in its travel by the longitudinal slots 36 and 37 arranged so as to permit the forward extension 34 to be actuated from

one to the other of the parallel guide ways formed in the guide frame, in the closed position of the lower sash, immediately below the lower extremity of the bar spring 24.

Means are provided for urging the lower outwardly extending portion of the spring 24 inwardly against the base plate 18 so that the spring will disengage the locking lever extension 34 and permit elevation of this member. This is accomplished by the provision of a transversely extending bolt 40 provided on its outermost extremity with an enlarged head 41 to permit convenient operation thereof. This bolt 40 is substantially greater in length than the width of the casing and projects through suitable openings formed adjacent the upper edge of the elevated walls thereof. A cotter 42 is secured to the intermediate portion of the bolt 40 and in the normal position of the bolt contacts with the outer side wall of the casing. This bolt is normally actuated to an outward position by the tension of a coiled spring 43 positioned about the bolt and interposed between the inner side wall of the casing and the cotter 42, causing the bolt to be urged outwardly so as to disengage the inner end of the bolt and permit the spring 24 to assume its normal outwardly directed position. When it is desirable to force the bar spring 24 inwardly against the base plate 18, the bolt 40 is forced inwardly against this spring member causing the inner end of the bolt to contact with the spring 24 and forcing this member against the base plate.

As it is desirable to securely enclose the locking mechanism to prevent tampering therewith, the cover plate 27 mounted on the elevated portion of the casing may be formed integral with the casing or securely positioned by welding or in any desirable manner. The angular swinging cover plate 28 is provided with side plates perforated adjacent the outer extremity and adapted to align with perforations formed in the side walls of the casing 25, this cover being locked in position by means of an angular pin 44 extending through the aligned openings formed in the cover and casing and securely fastened to the top rail of the lower sash frame by a staple 45 or in any suitable manner. Thus it is apparent, that a tightly sealed casing is provided preventing the operation of the interior locking mechanism by the application of an exterior tool.

In operation, it is apparent that the sashes when in their normal closed positions will be locked, that is, the lower sash cannot be elevated nor the upper sash lowered. This is brought about by the normal positions of the locking lever extension 34 and the bar spring 24, the lower extended position of this spring assuming an overhanging position relative to the lever extension so that

- the sash frames are locked in position. To elevate the lower sash, it is necessary to press firmly upon the bolt 40 causing this member to contact with the lower extending portion of the spring 24 and urging this member inwardly toward the upper sash frame so that the extension 34 may be elevated on the outer side of the spring. It is to be noted that the end of the extension 34 is spaced from the guide way base plate 18 sufficiently to permit compression of the bar spring 24, so that when the leaf spring is pressed against the base plate the locking lever extensions may be freely elevated.
- When it is desirable to partially elevate the lower window sash the knob 39 mounted on the locking lever is pushed toward the right causing the extension 34 to be in alignment with the right hand guide way.
- The bolt 40 is then forced inwardly so as to contact with the spring 24 and the lower sash may be elevated. The upward movement of the sash is, however, limited in this guide way as the extension 34 will necessarily contact with the end plate 22 and prevent elevation of the sash beyond a predetermined height. This is arranged to permit the window to be opened sufficiently for ventilating purposes but insufficient to permit the passage of a person's body so that an intruder could not enter the dwelling. If, on the other hand, it be desirable to elevate the lower sash its full length, the locking lever is actuated to the left, so that the extension 34 will be in alignment with the left hand guide way. As in the first instance, it is then necessary to force the bar spring inwardly by means of the bolt 40 and elevate the lower sash, the lock bolt extension in this instance traveling entirely through the guide way and permitting the sash to be raised upwardly against the head rail of the window frame. It is to be noted that the full length elevation of the window sash can only be accomplished by interior operation of the spring bolt 40 so that elevation of the window cannot be accomplished by exterior movement. In order to shift the locking lever extension 34 from one guide way to the other, it is necessary that this member be lowered below the lower extremity of the partition strip 17 necessitating the release of the spring 24 and operation of the bolt, before again raising the sash.
- From the foregoing structure it is apparent that an apparatus of simple design is provided whereby window sash frames will be automatically locked against opening movement when returned to their normally closed position. Elements are provided, however, for releasing the locking member so that the window may be opened to a limited position. The mechanism may be furthermore operated so as to permit the entire opening of the window by operation of an element on the interior side thereof so that unauthorized opening of the window to permit entering is prevented. The device is easily operable and arranged so as to permit convenient operation of the locking mechanism while moving the window sash.
- It is to be understood that the form of my invention herewith shown and described is to be taken as the preferred example of the same and that various changes as to the shape, size and arrangement of parts may be resorted to without departing from the spirit of the invention, or the scope of the subjoined claims.
- Having thus described my invention, I claim:
1. A window sash lock comprising, in combination, a locking mechanism adapted to be mounted on the lower sash of a window, a guide frame adapted to be mounted on the upper sash in co-acting position with the locking mechanism, a bar spring secured to the lower end of the guide frame engageable with the locking mechanism, and means for disengaging the bar spring from the said locking mechanism.
  2. A window sash lock comprising, in combination, locking mechanism including a casing, a lever movably mounted in the said casing, the said lever being provided with a horizontal extension, a guide frame embodying a pair of guide ways engageable with the said locking lever, a bar spring having its lower end extending outwardly from the guide frame engageable with the locking lever extension, and a transversely slid able bolt mounted in the locking mechanism casing adapted to compress the spring to permit movement of the locking lever.
  3. A window sash lock comprising, in combination, locking mechanism including a rectangular casing, means for securing the said casing upon the lower window sash, a locking lever movably mounted in the said casing, the said locking lever having a horizontal extension formed on one end and a vertical operating extension on the opposite end, a guide frame mounted on the upper window sash in co-acting relation with the locking mechanism, the said guide frame embodying a guide way enclosed at one end to permit restricted movement of the lower sash, and an open guide way to permit unrestricted movement of the sash, the said horizontal extension of the locking lever being movable in the said guide ways, a bar spring secured to the said guide frame adapted to normally engage the locking lever extension against elevated movement of the lower sash, and means mounted on the locking mechanism casing for releasing the said spring to permit movement of the sashes.

4. In combination with a window frame including an upper sash, and a lower sash, a sash lock comprising, a locking mechanism including a rectangular casing, means for securing the said casing upon the lower sash, an angular locking lever slidably mounted in the said casing having a horizontal extension, and a spring release bolt transversely slidable in the said casing; a guide frame secured to the upper sash in co-acting relation with the locking mechanism embodying, a guide way provided with a stop member, and an open guide way, the horizontal extension of the locking lever being slidably movable in the said guide frame, and a resilient bar spring secured to the guide frame having its lower end

normally extending outwardly so as to engage the horizontal extension of the locking lever, this spring being movable through 20 the medium of the transverse spring bolt to release the locking lever extension and permit movement of the sashes.

5. A window sash lock comprising, a movable locking element, a guide frame 25 operatively associated with the locking element, a resilient engaging member mounted in the lower portion of the guide frame engageable with the locking element, and means for disengaging the resilient member 30 so as to release the locking element.

In testimony whereof I affix my signature.

TREMONT W. RICKEL.
